UNITED STATES PATENT OFFICE.

JAMES IRVIN CHEESMAN, OF ALTOONA, PENNSYLVANIA, ASSIGNOR OF ONE-
THIRD TO CHARLES BALTZELL, OF SAME PLACE.

MACHINE FOR MAKING WELDED CHAINS.

SPECIFICATION forming part of Letters Patent No. 423,731, dated March 18, 1890.

Application filed August 13, 1889. Serial No. 320,622. (No model.)

To all whom it may concern:

Be it known that I, JAMES IRVIN CHEESMAN, a citizen of the United States, and a resident of Altoona, in the State of Pennsylvania, 5 have invented a new and useful Improvement in Machines for Making Welded Chains, of which the following is a specification.

This invention relates to mechanical devices for bending and welding straight blanks 10 to form links and for interlocking the links with one another as they are successively completed to form chains.

The invention consists in certain novel combinations of parts, hereinafter set forth 15 and claimed, its object being to effect the required movements, or, in other words, to hold, bend, and weld the heated link-blanks, to interlock the links, and to handle the chain by simple machinery performing most of its 20 functions automatically, and adapted to be attended by unskilled workmen.

Five sheets of drawings accompany this specification as part thereof.

Figure 1 of the drawings represents a side 25 elevation of a butt-weld machine and a vertical section of its base, illustrating the present invention. Fig. 2 represents a top view of the same with the left-hand side of the machine, as seen in Fig. 1, at the bottom of the 30 figure. Fig. 2^x represents an inverted plan of the main part or hub of the chain-turner detached. Fig. 3 represents a vertical section on the line 3 3, Fig. 1, some of the parts in the plane of section being shown in elevation. Fig. 4 represents a sectional plan view in the two planes indicated by the line 4 4, Fig. 1. Fig. 5 represents a sectional plan view of the parts below the line 5 5, Fig. 1. Fig. 6 represents an elevation of a lap-weld 35 machine, illustrating another species of the same invention in part. Fig. 6^x is a detail perspective view. Fig. 7 represents a plan view of that part of said lap-weld machine between its base and the line 7 7, Fig. 6, with the left hand side of the machine, as seen in Fig. 6, at the bottom of the figure; and Fig. 8 represents another elevation of this part of said lap-weld machine, showing said left-hand side of the same. 40 Like letters of reference indicate corresponding parts and correspondingly-num- bered arrows indicate like motions in the several figures. The full-line arrows in every instance represent the next succeeding movements and dotted arrows the return movements of the respective parts. 55

In erecting either of the two chain-machines represented by the drawings I mount its base B, upon a foundation A, Fig. 1, containing a vertical chain-pit C, and the machine comprises a tubular pillar D, in line with said pit; horizontal ways E E at the top of said pillar; a pair of former-slides F F, working in said ways and carrying at their inner ends the parts f or f² of a suitable former; horizontal ways G or G² at right angles to said ways E; bending-slides H or H², working in said ways G²; an annular horizontal wheel I, revolved back and forth around the pillar D, as illustrated by arrows 1^a 1^b, by suitable gearing J, and having its motion limited, as by stop-lugs s s' on the wheel and pillar, respectively; vertical shafts K K, turning back and forth, as illustrated by arrows 2^a 2^b, and transmitting motion 60 from said wheel to said former-slides F for periodically closing and reopening the former, as illustrated by arrows 3^a 3^b; levers L L, actuated by said wheel and reciprocating said bending-slides H H², as illustrated by arrows 4^a 4^b; a turning-hub M, which occupies the upper part of the bore of the pillar D and receives a quarter - turn back and forth, as illustrated by arrows 5^a 5^b, to turn the chain so that the upper end of its last- 65 completed link shall be at right angles to the blank for the next link; a hand-rod N, connected with said hub M for so turning it, and a hand-lever O, connected with devices hereinafter described for lowering the chain as 70 successive links are completed. The movements of said hand-rod are illustrated by arrows 6^a 6^b and those of said hand-lever by arrows 7^a 7^b. The accessories and details of said shafts K, levers L, hub M, hand-rod N, 75 and hand-lever O, so far as they are at all essential to the invention, are likewise common to both machines and will now be pointed out. Said shafts K are mounted in suitable bearings, as b b', in the bases of the ways E 80 and below the same, so as to depend above the wheel I, and they are provided at their 85

100

lower ends with rigid horizontal arms *a*, three on each, which are successively engaged by tappets *t* *t*', carried by said wheel at its perimeter. A short crank-arm *c*, Figs. 2 and 4, fast on the upper end of each shaft within a suitable recess *r*, coacts with a transverse slot or groove *g* in the bottom of each former-slide *F* for transmitting motion thereto, and also supports the shaft vertically, while the peculiarly-shaped recess *r* coacts therewith to limit the partial rotations of the shaft to the proper extent.

The levers *L* work on pivots *p*, suitably supported in brackets *b*⁸, so as to be transverse to the central vertical planes of said bending-slides *H*. The lower end of each lever, being suitably shaped, is engaged successively by horizontal inclines *i* *i*', carried by the wheel *I*, and serving, respectively, to impart to the lever its effective and return strokes. The bar which forms each incline (marked *i*) works on a vertical pivot and is held in effective position by a spring *s*⁸, so that in the return movement of the wheel the lever engaging with the back of the bar may displace the same and be unaffected thereby. The inner end of the bar forming each incline *i*' terminates so as to revolve outside of the lower end of the lever in its position of rest. The upper ends of the levers *L* are coupled to the slides *H* by telescoping rods *r*', (best seen at the left in Fig. 3,) which are cleared by the castings that form the ways *G* *G*', as seen in Figs. 3, 4, and 6.

The turning-hub *M* of each machine consists of a hollow vertical cylinder fitted to the bore of the pillar *D*, so as to turn freely, and having a circumferential shoulder *s*⁴, Fig. 2², which coacts with a supporting-shoulder *s*⁵, Fig. 3, within the pillar. Its upper end terminates as close to the plane of the former as is convenient, and is provided with internal spring-fingers *f*', which depend at the outer walls of its cruciform interior. The lower free ends of these fingers normally occupy their outermost positions, and are provided on their backs with projections which extend through holes in the walls of the hub and revolve in a circumferential groove *g*', Figs. 3 and 4, within the pillar *D*.

The hand-rod *N* is connected with the hub *M* by a lever-arm *a*', Fig. 5, which projects rigidly from the latter and works in a horizontal slot *s*⁶ in the pillar *D*, which limits its movement and that of the hub to ninety degrees. A suitable guide-bearing *b*⁴ for the rod is conveniently attached to said bracket *b*⁸.

The hand-lever *O* turns on a pivotal support *p*', which may project from any fixed part of the machine, and is connected above and below its fulcrum by rods *r*² with a pair of releasing-levers *r*³, the latter in turn acting upon diametrically-opposite horizontal thrust-bars *t*², which at their inner ends engage with the projections on the backs of the fingers *f*' of the turning-hub *M* in successive pairs to press the fingers inward, so as to grasp and

support the link last finished. One of the thrust-bars is exposed to view in the lower plane of section in Fig. 4. Each of them works in a suitable guide *g*² at its inner end, and is supported at its outer end and pressed inward with the requisite force by a spring *s*⁷, which is conveniently bolted to the outer end of the base of the way *E* above it. Where they cross the shafts *K* the thrust-bars are slotted, as shown in Fig. 4, and their inner ends, together with said projections on the backs of the fingers *f*', are so shaped as to engage with each other automatically when the hub *M* is turned by the hand-rod *N*.

In the machine represented by Fig. 1 to 5, inclusive, the former parts *f*, carried by the slides *F*, are four in number, a pair being permanently connected with each slide by dovetail tongues and grooves *d*, Fig. 1, for example, and normally held apart by a spring *s*⁸, acting upon slotted levers *s*⁹. Both planes of division are central and vertical, and the respective parting surfaces are grooved to accommodate between them the upper end of the link last finished and the blanks which are to be welded around the former, as best seen in Figs. 2 and 3.

After the former-slides *F* move inward, as illustrated by the arrows 3^a, to close the former, a spreader *P*, which is normally supported in elevated position by a hand-lever *Q*, turning on a pivotal post *R*, is lowered between the respective end pairs of the former parts, as represented by the dotted outline thereof in Fig. 3, so as to keep the former extended as regards its length. A pair of heated blanks *x* are then dropped endwise upon suitable gage-surfaces *g*⁸, so as to stand vertically at the ends of the extended former in line with its circumferential groove and so as to project equally above and below its central horizontal plane, as represented by dotted outlines in Fig. 3. The inward movement of the bending-slides *H* (illustrated by the arrows 4^a) next follows, and when the respective blanks have reached **U** shape the spreader *P* is withdrawn by the lever *Q*, as illustrated by the arrow 8, Fig. 3, which permits the bending-slides to bring the ends of the blanks forcibly together and simultaneously effect the two butt-welds which complete a link, the end parts of the former moving freely toward each other, as illustrated by arrows 9, Figs. 2 and 3. For this style of work the former-slides *H* are bifurcated, and each is provided at its inner ends with a pair of grooved anti-friction rollers *r*⁴, and the upper end of the turning-hub *M* is sunk below the top of the pillar *D*, and the latter is recessed so as not to interfere with the movements of the blanks. When the blank ends come together, one pair of them is welded within the upper end of the last preceding link, and the two links are thus interlocked. The bending-slides are immediately retracted, as illustrated by the arrows 4^b, followed by the retraction of the slides *F*, as illustrated by arrows 3^b, which

120
125
130
135

drops the newly-finished link into the recess at the top of the pillar D. The operator then takes it by his tongs with one hand, and with the other hand manipulates the turning-hub 5 M and thrust-bars t^2 by means of the hand-rod N and hand-lever O, as illustrated by the arrows 5^a 6^a 7^a, so as to give the chain a quarter-turn and to lower the same, so that the new link shall occupy the position in which 10 the upper link is shown in Fig. 3. Another pair of blanks is then introduced, the operation as above described is repeated, and so on until the required length of chain is completed.

15 In the machine represented by Figs. 6 to 8, inclusive, the two parts f^2 of the former are fixedly attached to the respective slides F and are provided, respectively, at top with a central anvil-projection a^2 and a matching recess a^3 , and both former parts are provided at bottom with rigid supporting projections p^4 , Fig. 6^x, and central gage-recesses r^5 to engage, respectively, with the current blank x^2 and with the upper end of the link l^2 , with 20 which it is to interlock. The blanks x^2 are straight rods with scarfed ends. One is shown in position in Fig. 7. Longitudinal grooves g^3 in the otherwise flat tops of the bending-slides H^2 receive and hold the blanks. A gage-stop g^4 in one of these grooves is adjustable for blanks for longer or shorter links. The bending-slides H^2 carry a single grooved anti-friction roller r^6 at the inner end of each, and their ways G^2 are in turn guided by ways S, 25 so as to slide vertically, as illustrated by arrows 4 4^c. After the former is closed above the blank, as represented by dotted outlines in Fig. 6 and by arrows 3^a in Fig. 7, the ways G^2 are elevated to the position in which they are shown in Fig. 8, which movement (illustrated by said arrow 4) effects the primary bends of the blank, as represented at the right in Fig. 8. The bending-slides are next reciprocated, one after the other, as illustrated by 30 the arrows 4^a 4^b and by full and dotted outlines in Fig. 8, to complete the bending operation. The ways are then lowered, as represented by the arrows 4^c, carrying with them the retraced bending-slides. Said vertical 35 movements of the ways G^2 , which distinguish this bending mechanism, are effected by a pair of segmental racks T, carried by the wheel I and concentric therewith, toothed sectors U, mounted in fixed supports and meshed by 40 said racks, respectively, and pitmen V, connecting said sectors with the sliding ways. Vertical ways W for a drop-hammer X, having a suitably-grooved face, are supported in proper position by a frame Y, which projects 45 upward from the top of the pillar D, and the hammer is connected by a rod Z with suitable means for elevating and dropping it, such as those of an ordinary steam-hammer. As soon as the last bending-slide is retraced the 50 hammer drops and effects the single lap-weld of the link that is being made, the former, with its said anvil projection a^2 , supporting

the overlapping ends of the blank, while the supporting projections p^4 , with the still elevated bending-slides, keep the bent blank in shape around the former until it is so welded. The hammer is then re-elevated, the bending-slides descend with their guides, as aforesaid, the former-slides are separated, and the newly-finished link with the chain to which it has been added are manipulated with the aid of the hand-rod N, actuating the turning-hub M, and the releasing-lever O, retracting the thrust-slides t^2 , as in the machine first described.

In either machine as the wheel I is driven by the gearing J in the direction represented by the arrows 1^a from the position of rest in which it is shown in Figs. 1 to 5 and in Fig. 7 and in full lines in Fig. 6, the tappets t come in contact immediately with the outermost of the arms a of the vertical shafts K, and the motion of the latter is kept up by the contact of the tappets t with the next succeeding arms. Said shafts K thus receive their semi-rotations, (represented by the arrows 2^a), the former-slides F receive their inward movements, (represented by the arrows 3^a), and the formers are prepared for the bending operation. In the lap-weld machine, Figs. 6 to 8, the racks T next engage with the sectors U, and through the pitmen V the sliding ways G² receive their simultaneous upward movement, (represented by the arrows 4, Fig. 6,) leaving them in the elevated position in which they are shown in Fig. 8. The inclines i next engage with the levers L, and the bending-slides H H² receive their inward movements, (represented by the arrows 4^a), to complete the bending operation. In the butt-weld machine, Figs. 1 to 5, the bending-slides H are moved simultaneously. In the lap-weld machine the bending-slides H² are moved one after the other, as aforesaid, as illustrated by full and dotted outlines in Fig. 8, so as to lay the respective ends of the blanks in proper order. In the butt-weld machine, Figs. 1 to 5, the completion of the simultaneous inward movement of the bending-slides H, with their forks in contact with the ends of the divided former, effects the welding of the link, the spreader P having been withdrawn immediately before such contact. The inclines i' next come in contact with the levers L, and the bending-slides receive their outward movements. (Represented by the arrows 4^b.) This completes the cycle of operations effected by each turn of the wheel I. (Illustrated by said arrows 1^a.) In the lap-weld machine the hammer X, Fig. 6, now descends, effecting the single weld of the link, and is retracted to the elevated position in which it is shown. In the return movement of the wheel I, (represented by the arrows 1^b), the inclines i' first pass the levers L without touching them, and the inclines i yield outwardly in contact therewith, so as to leave said levers and the slides H H² in their retracted positions. In the lap-weld machine the racks T next come in contact with the

sectors U, and through the pitmen V lower the ways G², as represented by the arrows 4²; Fig. 8, and finally the tappets t' t in this order, coacting with the arms a, impart to 5 the shafts K their reverse movements, (represented by the arrows 2^b.) and the former-slides F thus receive their outward movements. (Represented by the arrows 3^b.) This returns the automatically-moving parts of both 10 machines to the positions of rest in which they are shown in Figs. 1 to 5 and in Fig. 7 and by full lines in Fig. 6. The newly-finished links, the chains to which they have been 15 added, and new blanks are next adjusted for the succeeding operation of each machine, as before described.

Details which have not been specified may be of any approved description, and I do not limit my respective claims, hereinafter stated, 20 to mechanical details other than those essential to each combination.

It is intended that all the parts shall be constructed in a workmanlike manner, of suitable metals, and with shapes and proportions 25 appropriate to their respective functions.

It is further intended that the former parts and like portions of the respective machines shall be removable, and that the machines shall be provided with interchangeable parts 30 for these positions in customary manner, so as to adapt the machines to make links of different proportions. In some cases a single thrust-slide t² may suffice, and individual parts of the invention may be embodied in 35 such machines without the remainder. Other like modifications will suggest themselves to skilled machinists.

The butt-weld machine, Figs. 1 to 5, is selected for all claims herein that do not apply 40 to both machines.

Having thus described said improved machines, I claim as my invention and desire to patent under this specification—

1. In combination with a pair of horizontal 45 former-slides carrying the parts of a divided former, a horizontal wheel carrying tappets, vertical shafts having arms engaged by said tappets, and means, substantially as described, for revolving said wheel back and forth and 50 for transmitting motion from said shafts to said slides.

2. In combination with a pair of bending-slides, a horizontal wheel carrying inclines, a pair of levers engaged by said inclines at one 55 end, and connections between their other ends and said slides, substantially as hereinbefore specified.

3. In a machine for making chains, a turning-hub having a cruciform interior provided 60 with longitudinal holding-fingers, substantially as hereinbefore specified.

4. In a machine for making chains, a vertical turning-hub having a cruciform interior, a tubular pillar inclosing and supporting the 65 same and having a horizontal stop-slot, and devices, comprising a lever-arm which projects from said hub through said slot, for giv-

ing the hub a quarter-turn back and forth at will for interlocking the links, substantially as hereinbefore described.

5. The combination of a vertical turning-hub having a cruciform interior provided with longitudinal holding-fingers which have external projections at their free ends and are normally retracted, a thrust-bar arranged to engage with one of said projections at right angles to the vertical plane of the blank or blanks, a spring projecting said bar inward, and means, as a hand-lever and connections, for retracting the bar at will to lower the 80 chain, substantially as hereinbefore specified.

6. The combination of a vertical turning-hub having a cruciform interior provided with longitudinal holding-fingers at its several outer walls which have external projections at their free ends and are normally retracted, a pair of thrust-bars diametrically opposite each other in a vertical plane at right angles to that of the blank or blanks, springs projecting said bars inward, a retracting hand-lever, and connections between the latter and both bars, substantially as hereinbefore specified.

7. The combination, in a machine for making welded chains, of a foundation provided with a chain-pit, a tubular pillar erected thereon communicating with said pit and provided with an internal holding and turning hub, horizontal former-slides and bending-slides with their ways at right angles to each other at the top of said pillar, a horizontal annular wheel revolving back and forth around the pillar beneath said slides, mechanisms transmitting motion to the latter from said wheel automatically, and independent means for turning said hub and lowering the chain therein by hand, substantially as hereinbefore specified.

8. In combination with bending-slides working toward each other, a link-shaping former divided transversely, and a spreader which keeps the respective end parts of the former separated during the bending operation and is retracted to permit them to come together for an immediately-succeeding butt-welding 115 operation, substantially as hereinbefore specified.

9. In combination with a pair of bending-slides working toward each other, a link-shaping former divided transversely and in the plane of its peripheral groove, its respective side parts being carried by former-slides at right angles to said bending-slides, substantially as hereinbefore specified.

10. In combination with a pair of bending-slides working toward each other, a link-shaping former divided transversely and in the plane of its peripheral groove, its respective side parts being carried by former-slides at right angles to said bending-slides, together 130 with springs and connections which keep the former parts normally separated endwise, substantially as hereinbefore specified.

11. In combination with a link-shaping

former divided transversely and in the plane of its circumferential groove, a pair of bending-slides having their inner ends bifurcated and provided at their respective extremities 5 with grooved anti-friction rollers, substantially as hereinbefore specified.

12. The combination, with a tubular vertical pillar having an internal turning-hub and a recessed upper end extending above said 10 hub, of a pair of horizontal former-slides at the top of said pillar, carrying at their inner

ends the parts of a vertically-divided link-shaping former, and a pair of horizontal bending-slides working at right angles to said former-slides and having their inner ends bifurcated and provided with anti-friction rollers at their respective extremities, substantially as hereinbefore specified. 15
